United States Patent Office

Des. 198,772
Patented July 28, 1964

198,772

FROZEN CONFECTION

Richard J. Cowling, Tenafly, N.J., and David L. Hendrick, Commack, N.Y., assignors to Joe Lowe Corporation, Englewood, N.J., a corporation of Delaware

Filed Jan. 23, 1964, Ser. No. 78,337

Term of patent 14 years

(Cl. D82—2)

FIG. 1

FIG. 2

FIG. 3

The essential features of the design reside in the portions shown in solid lines.

We claim:

The ornamental design for a frozen confection, substantially as shown and described.
